UNITED STATES PATENT OFFICE

OSCAR L. LAWSON, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

THREAD-MEASURING MECHANISM FOR SHOE-SEWING MACHINES

Application filed May 26, 1926. Serial No. 111,859.

This invention relates to shoe sewing machines and especially, although not exclusively, to machines of the type shown and described in an application for Letters Patent filed by James H. Reed, March 10, 1922, Serial No. 542,666. A machine of this type is adapted to sew a through-and-through lock stitch seam through the insole, outsole and upper of a shoe, and includes a straight hooked needle and a shuttle supplying a shuttle thread at the upper side of the work, while at the under side of the work is a work supporting horn provided with a looper or whirl which supplies a cop or needle thread, together with take-up and stitch setting mechanism to draw the needle loop over the shuttle and set the stitch.

The present invention relates particularly to mechanism, applicable to machines of the above and similar types, for controlling the cop or needle thread, and particularly for drawing the latter from the source of supply in measured quantities in accordance with the length of stitch and the thickness of the work and for holding the same for the action of take-up and stitch setting mechanism. The primary object of the invention is to provide improved thread measuring and clamping mechanism which will correctly and reliably perform its intended functions irrespective of the speed of operation of the machine, thereby permitting such a machine to be run at a higher speed than has heretofore been possible in machines of this type.

The foregoing and other objects of the invention, together with means whereby the same may be carried into effect, will best be understood from the following description of one form or embodiment thereof illustrated in the accompanying drawings. It will be understood however that the particular construction described and shown has been chosen for illustrative purposes merely, and that said invention, as defined by the claims hereunto appended, may be otherwise embodied without departure from the spirit and scope thereof.

In said drawings:

Fig. 1 is a side elevation, partly in sec-

tion, of a substantially complete shoe sewing machine embodying the invention.

Figs. 2 and 3 are sections taken substantially on the lines 2—2 and 3—3, respectively, Fig. 1.

Fig. 4 is a detail front elevation of the thread pull-off member and thread clamps.

Fig. 5 is a detail section taken substantially on the line 5—5, Fig. 4.

Fig. 6 is a similar view showing the parts in a different position.

In the embodiment of the invention shown, the frame of the machine comprises a hollow base 15 carrying the work supporting horn 16 and from which rises a standard 17 carrying at its top the frame-work 18 of the head. The horn 16 is of a size and shape to render it capable of being inserted into the toe of a shoe and is mounted in a bearing 19 secured to the front of the base 15 at the top of the latter. Said horn is provided with a journal portion 20 rotatably mounted in the bearing 19 in such a manner as to permit said horn to be turned as the sewing progresses. The needle 21, which is above the work A, is straight and is formed adjacent its pointed lower end with an open, loop-engaging hook, said needle being carried by a needle bar 22 guided for rectilinear reciprocating movement in the head 18. Within the tip of the horn 16, and therefore below the work or at the opposite side thereof from the needle 21, is a whirl 23 which is rotatably mounted in said horn and is provided with an eccentric opening through which the cop or needle thread passes loosely, and with an axial opening to receive the point of the needle when the latter descends to penetrate the work, whereby said whirl operates to form a loop about the needle immediately above the hook of the latter. Thereafter, as the needle rises, the loop so formed is drawn upwardly through the work. Above the work, or at the same side thereof as the needle, is an oscillating discoidal shuttle 26 carrying a shuttle thread, said shuttle having a hook or beak adapted, when the needle rises, to receive the loop of needle thread from the needle hook and pass it about the shuttle and shuttle thread. The machine also includes, below the work, mechanism acting

on the needle thread C to draw the needle loop over the shuttle and down upon the work, thereby completing the formation of the stitch, and thereafter to set the latter by drawing the thread locks into the material.

Said last named mechanism as herein shown is of the type more fully described in another application filed May 26, 1926, Serial No. 111,861, and includes a combined take-up and stitch setter 28 guided in the horn 16, and engaging the needle thread C between two fixed thread guides 29. The combined take-up and stitch setter 28 is connected to the free end of a lever 31 pivoted within the base of the horn to a bracket 14 having a hollow cylindrical stem 13 which extends axially through the journal portion 20 of the horn. The lever 31 is connected intermediate its ends with a slide 32 passing eccentrically through the stem 13 of the bracket 14 and reciprocated therein by a lever 33 one end of which engages an annular head 12 formed on the lower end of said slide. The needle thread is held for the action of the take-up 28 by a thread clamp 34, is drawn from the supply in measured quantities for each stitch by a combined thread pull-off and measuring device 35, and is also held for the action of the pull-off 35 by a second thread clamp 36, all as hereinafter more fully described.

The needle bar 22 and shuttle 26 are actuated through suitable connections, not shown in detail, from a horizontally disposed main or power shaft 38 journaled in the head 18 and receiving power from any suitable source through a pulley 39 loosely mounted thereon and connected therewith by means of a clutch 40 operated through suitable connections by a treadle lever 41 at the base of the machine.

Connected, as by spiral gearing 42, with the shaft 38 is a vertical shaft 43 which extends downwardly along or through the standard 17, is journaled at its lower end in a bracket 44 on the base 15, and carries a cam 45 for actuating the take-up lever 33.

The whirl 23 is operated by mechanism which as herein shown is of the type more fully disclosed in another application filed May 26, 1926, Serial No. 111,860 and includes angularly disposed shafts 46 and 47 in the horn 16, said shafts being connected with each other by gearing 48, the upper end of the shaft 46 being geared to the whirl 23, and the shaft 47 being connected by gearing 50 with a hollow vertical shaft 51 which extends axially through the stem 13 and carries a coaxial guide tube 11 for the thread C. The shaft 51 is connected by gearing 53 with one end of a horizontal cam shaft 54 journaled in bearings on the base 15 and connected at its opposite end by gearing 55 with the vertical shaft 43.

During the formation and setting of each stitch the work A is clamped upon the horn 16 by a presser foot 56 carried by a presser

foot bar 57 which is normally pressed downwardly by a spring 24 and is periodically raised to permit feeding of the work (by instrumentalities not shown in detail) by means of a bell-crank lever 58 actuated by a cam on the main shaft 38. The presser foot 56 may also be manually raised to permit removal and insertion of the work by a lever 59 engaging the presser foot bar 57 and connected by a link 60 with a second lever 61 connected by a link 62 with a treadle lever 63 at the base of the machine.

The thread measuring or pull-off member 35 comprises a rod guided for longitudinal movement in a bracket 64 secured to the exterior of the base 15 and in a second bracket 72 within the latter, said rod having in its end a notch or slot 65 through which the needle thread C passes between two stationary thread guides in the form of aligned openings 66 in a boss 67 formed on said bracket 64. The thread clamp 34 is located between the pull-off member 35 and the source of needle thread supply (not shown), while the thread clamp 36 is located between said pull-off member and the stitch-forming instrumentalities. Each of said thread clamps also comprises a rod guided for longitudinal movement in the brackets 64 and 72 and having a slot 68 through which the thread C passes, the slots 68 being in alignment with the thread guides 66 and with the notch 65 in the pull-off member, whereby the thread may be led in a straight line through the mechanism, as shown in Fig. 4. Each thread clamp rod is provided with a head, preferably in the form of a collar 69 and nut 70, constituting the movable thread gripping member adapted to clamp the thread against the face of the bracket 64, which constitutes the cooperating stationary thread gripping member, the rods being moved longitudinally to clamp or release the thread. Suitable means are provided to prevent turning of the rods 34 and 36 in the bracket 64, thereby preserving the alignment of the slots 68, said means as shown comprising guide pins 71 projecting from said bracket and engaging notches in the collars 69.

In operation, longitudinal movement of the pull-off member 35 from approximately the position shown in Fig. 5 to approximately the position shown in Fig. 6, with the thread clamp 34 open and the thread clamp 36 closed, causes the bottom of the notch 65 to engage the thread C and deflect it out of its normal alignment between the guides 66, thereby drawing from the source of supply a length of thread whose amount depends upon the extent of such deflection. Thereafter, the thread clamp 34 is closed and the thread clamp 36 opened to permit the stitch-forming instrumentalities to take up the thread so drawn off. In the embodiment of the invention herein illustrated, the range or

amount of movement of the pull-off member at each operation is constant, but the limits (i. e., the starting and stopping points) are automatically varied in accordance with the thickness of the work and are manually adjusted in accordance with the length of stitch. The outward limit of movement of the pull-off, or movement toward the position shown in Fig. 6, determines the extent of deflection of the thread and consequently the amount drawn from the supply.

In the operation of thread measuring mechanism of the type employing a variably actuated pull-off member, as heretofore constructed, difficulty has been encountered in the tendency of the pull-off member to overthrow when the machine is speeded up, thereby destroying the accuracy and consequently the utility of this mechanism, so that the speed of operation of the machine has been definitely limited, and it has been impossible to produce high speed machines of this type. In accordance with the present invention there is provided mechanism for variably actuating the pull-off member, which mechanism is of such a character as to actuate said member positively in both directions, thereby retaining at all times a positive control over said member and preventing any possibility of overthrow, so that the speed of operation of the machine is in nowise limited. As herein shown the mechanism for so operating the pull-off member, and also for alternately operating the thread clamps in the sequence described, is as follows:

Pivoted, as at 73 (Fig. 1), within the base 15, is a lever 74 having a cam roller or follower 75 engaging a closed path in the periphery of a cam 76 on the shaft 54. Guided for longitudinal movement on the lever 74, that is to say, for movement in a direction transverse to the direction of movement of said lever, is a slide 77, said slide as shown having slots 78 engaged by studs 79 projecting from said lever. The slide 77 is connected by a link 80 with one end of a lever 81 pivoted at 82 to the head 18 and connected at its opposite end with the presser-foot bar 57. The slide 77 is formed with an inclined groove 83 which is engaged by a stud or projection 84 (see also Fig. 2) on a slide 85 guided for longitudinal movement on the rod 35 but normally fixed thereon.

When the lever 74 is oscillated on its pivot 73 by the cam 76, the rod or thread pull-off member 35 is reciprocated to draw off and release the thread, as above described. The slide 77, with its inclined groove 83 engaged by the projection 84 on the rod 35, constitutes the operative connection between said rod and the lever 74. By reason of the inclination of the groove 83, the limits of movement of the rod 35, and consequently the amount of thread drawn from the supply, are determined by the position of the

slide 77 on the lever 74, which position is automatically controlled in accordance with the thickness of the work by its connection with the presser foot or work engaging member 56 through the presser foot bar 57, lever 81, and link 80. It will be seen that the pull-off rod is positively actuated in both directions and that, by reason of the engagement of the cam follower 75 in the closed path of the cam 76 and the permanent engagement of the stud 84 in the groove 83, said rod is at all times under the positive control of its actuating means, so that overthrow thereof is prevented irrespective of the speed of operation of the machine.

The limits of movement of the thread pull-off member may also be manually adjusted in accordance with the length of stitch by varying the position of the slide 85 on the rod 35. To this end, said slide is in threaded engagement with an adjusting screw 86 (see Fig. 2) having a head 87 which engages a peripheral groove 88 in a head 89 formed on the rod 35, thereby providing a micrometer adjustment which permits the setting of the parts with great accuracy.

The thread clamps are closed by springs 90 surrounding the rods 34 and 36 and interposed between the front wall of the base 15 and collars 91 fast on said rods. Said thread clamps are opened to release the thread by means of a rocker 92 carrying abutment screws 93 and movable in opposite directions to bring said abutment screws into operative engagement with the ends of the rods 34 and 36 alternatively and move the same in opposition to the springs 90. The rocker 92 is carried by a shaft 94 (Fig. 3) journalled in the bracket 72 and having an arm 95 carrying a cam roller or follower 96 which engages a path in the periphery of a cam 97 on the shaft 54.

It will be seen that, in addition to the advantages above pointed out, the mechanism described is very simple and compactly arranged, the single shaft 54 in the base 15 being employed to actuate the whirl, the thread pull-off member, and the thread clamps.

Having thus described my invention, I claim:

1. In a shoe-sewing machine, in combination, a work-engaging member, a thread pull-off member, an actuator, and a slide guided on said actuator for movement in a direction transverse to the direction of movement of the latter and operatively connected with said work-engaging member, said slide having an inclined groove, and said pull-off member having a projection engaging said groove.

2. In a shoe-sewing machine, in combination, a work-engaging member, a thread pull-off member, a cam having a closed path, a lever having a cam follower in said path, and

a slide guided on said lever for movement longitudinally thereof and operatively connected with said work-engaging member, said slide having an inclined groove, and said pull-off member having a projection engaging said groove.

3. In a shoe-sewing machine, in combination, a constant throw thread measuring member, an actuator therefor, and means including a micrometer adjustment for operatively connecting said member and actuator and varying the limits of movement of said member.

4. In a shoe-sewing machine, in combination, a thread measuring plunger, an actuator therefor having a groove, a slide guided on said plunger and having a stud engaging said groove, and an adjusting screw connecting said slide and plunger.

5. In a shoe machine, in combination, sewing devices including a hook needle, a thread pull-off member comprising a plunger to engage the thread, means for imparting a constant positive lengthwise reciprocating motion to the plunger in each direction, and means for varying the limits of movement of the plunger to vary the effective pulling-off action of the plunger on the thread.

6. In a shoe machine, in combination, sewing devices including a hook needle, a work supporting horn, a whirl contained within the horn, a thread pull-off member comprising a plunger to engage the thread, means for guiding the thread at each side of the plunger, constant throw actuating mechanism for imparting a positive lengthwise reciprocating movement to the plunger in each direction, and an adjustable connection between said actuating mechanism and the plunger to vary the limits of movement of the plunger to regulate the amount of thread pulled off in accordance with the thickness of the work.

7. In a shoe machine, in combination, sewing devices including a hook needle, a work supporting horn, a whirl contained within the horn, a thread pull-off member comprising a plunger to engage the thread, means for guiding the thread at each side of the plunger, a constant throw actuating mechanism for imparting a positive lengthwise reciprocating movement to the plunger in each direction, an adjustable connection between said actuating means and the plunger to vary the limits of movement of the plunger to regulate the amount of thread pulled off in accordance with the thickness of the work, and an adjusting means between the plunger and said adjustable connection.

8. In a sewing machine, in combination, a thread measuring reciprocating plunger to engage the thread, an actuator therefor adapted to impart a constant throw to said plunger, and means for operatively connect-

ing said plunger and actuator including a micrometer adjustment for determining the limits of movement of the plunger.

In testimony whereof I affix my signature.

OSCAR L. LAWSON.
